STILL

Alexander I. Newman, Chicago, Ill., assignor to
Precision Scientific Company, Chicago, Ill., a
corporation of Illinois

Application July 13, 1939, Serial No. 284,310

4 Claims. (Cl. 202—189)

The invention relates to improvements in stills and finds particular utility as applied to apparatus for distilling water.

The general aim of the invention is to provide an improved still which is small and compact in size so as to be readily portable, is entirely automatic in operation, includes no moving parts which are likely to wear and get out of order, can be readily cleaned, and which, though rugged in construction and efficient in operation, is low in cost.

Another object of the invention is to provide a still in which cleaning of the active surfaces is made easy by arranging them in separable casting sections so that when these sections are detached from each other all of the active surfaces of the still will be completely exposed for cleaning.

A further object is to provide a still in which the cooling medium for the condenser may be utilized to cool, by a desired amount, the liquid distillate produced.

Further objects and advantages of the invention will become apparent as the following description proceeds, taken in connection with the accompanying drawing, in which:

Figure 1 is a general perspective view of a still embodying the invention.

Fig. 2 is a vertical sectional view, on a somewhat reduced scale, of the still of Fig. 1.

Fig. 3 is an exploded perspective view, on a reduced scale, of the still of Fig. 1.

By way of exemplification the invention has been shown herein as embodied in a small portable water still adapted for laboratory or industrial use in instances where a capacity of about a quart per hour is adequate. It will be obvious, however, to those skilled in the art that various features of the invention are applicable to other forms or sizes of stills. Accordingly, even though one particular embodiment of the invention has been shown and described in some detail there is no intention to thereby limit the invention to such embodiment, but, on the other hand, I intend to cover all modifications and alternative constructions falling within the spirit and scope of the invention as expressed in the appended claims.

In the illustrative construction (Fig. 1) the still shown is of generally cylindrical shape, being compact and easily portable. Raw water for distillation as well as for condenser cooling is supplied through a single inlet 10 by a suitable hose (not shown) and the distilled water is bled off through an outlet spout 11. In brief, the raw

water from the inlet 10 is discharged to a condenser cooling water chamber 12 (Fig. 2) where it cools the surface of the condenser. From this chamber 12 water is overflowed through a pipe 13 to a cup 14 from which it passes into an evaporating chamber 15. In this latter chamber the water is boiled and the vapor passes into a condensing chamber 16 where it is condensed and the distillate 17 collected. Finally, this distillate is drawn off through the outlet 11.

In order to facilitate cleaning of the still's active surfaces it is made up in a series of separable units or sections, here shown (Figs. 2 and 3) as three in number and designated generally by the letters A, B and C. In general the lower section A embodies a vessel defining the evaporating chamber 15 and also includes a heating unit for this vessel; the intermediate unit B comprises a vessel fashioned to receive the distillate 17; and the upper section C embodies a water cooled condenser unit. By simply separating these three sections all of the active surfaces of the still are exposed for cleaning as will hereinafter appear in greater detail.

The lower unit A includes an outer cylindrical sheet metal casing 18 (Fig. 2) in the upper portion of which is removably mounted a cup-shaped metal evaporating pan 19, defining the evaporating chamber 15. Any suitable heating unit may be located beneath the evaporator pan 19, this unit, in the present instance, being illustrated as a resistance type electrical heater 20 controlled by a switch 21. The cup 14 is fixed on the side of the unit A by an inlet nipple 22 through which it communicates with the evaporator pan 19. This nipple 22 is fixed to the cup 14 and is threaded in the side of the removable pan 19 to hold the latter in place. A vertical overflow pipe 23, which may be connected with 40 a waste drain through a rubber hose (not shown), serves to regulate automatically the level of raw water 24 in the evaporator pan 19. Water enters the cup 14 from the pipe 13 and fills the cup and evaporating pan 19 until it reaches the top of the overflow pipe 23. Upon reaching this level any excess water is drained off through the pipe 23.

The intermediate unit B includes a cylindrical sheet metal casing 25 dimensioned to telescope 50 within the top of the lower unit casing 18. An annular bead 26 is fashioned in the casing 25 and rests on the rolled-edge rim of the lower unit casing 18 to locate the intermediate unit casing 25.

Two dome-shaped transverse sheet metal par-

titions 27 and 28 are fixed in the intermediate casing 25. The lower partition 27 has a flanged edge 29 which is press-fitted about the lower edge of the casing 25 while the peripheral edge of the upper partition 28 is fastened to the inner wall of the casing. The lower partition or dome 27 constitutes a top wall for the evaporating chamber 15, and the upper dome 28 cooperates with the casing 25 to define a vessel for collecting the distillate 17. A channel through which vapor may rise from the evaporating chamber 15 to the condensing chamber 16 is formed by a vertical metal tube 38 projecting through the centers of the partitions 27, 28 and fixed to them.

In order to prevent raw water from reaching the condensing chamber 16 even during violent boiling in the evaporating chamber 15 a baffle plate 31 is located at the lower or inlet end of the tube 38. This baffle may be square in shape and fastened at its corners to the dome 27. Consequently, water vapor rising in the evaporating chamber 15 passes around the marginal edges of the baffle 31 and thence into the tube 38 which is of somewhat smaller cross section than the baffle.

The upper section C includes a cup-shaped sheet metal casing 32 on the outer wall of which is welded an annular plate 33 for supporting it on the top of the intermediate casing section 25. A depending flange 34 on the plate 33 is telescoped over and fits snugly about the rolled edge on the upper rim of the casing 25. The center of the casing 32 is deeply dished to form a dome 35 defining the condenser chamber 16. With the casing so fashioned the condenser cooling water chamber 12 has a lower annular portion 12^a which completely surrounds the condensing chamber 16.

The casing 32 is dimensioned so that the lower portion of the annular cooling chamber 12^a projects below the distillate outlet 11 and into the body of distillate 17. The cooling water entering the chamber 12 is directed from the inlet 18 down through a pipe 36 into the bottom of the annular chamber 12^a. In this way the distillate 17 is effectually cooled by the entering cooling water, and the degree of cooling for the distillate can be regulated by varying the amount of the cooling water which is supplied the condenser. The top of the condenser is closed by a removable sheet metal cover 37 telescoped within the top of the casing 32.

To utilize a maximum amount of the surface of the casing 32 for condensing purposes, one or more equalizing tubes 32^a (Fig. 2) are arranged to establish communication between the chamber 16 and the space or chamber lying between the outer wall or jacket portion of the casing 32 and inner wall of the casing 25. In this way water vapor passes out to this latter space through the tubes 32^a and is condensed on the outer surface of the condenser casing 32. Furthermore, the pressure is equalized, through the tubes 32^a, in the two condensing spaces despite the water seal formed at their lower ends by the pool of liquid condensate.

To prevent contamination of the distillate by volatile gases, such as carbon dioxide, chlorine and ammonia, provision is made for expelling these gases from the top of the still before the vapors are condensed, thereby rendering the distilled water gas-free. For this purpose a vertical tube 38 is let into the top of the condenser dome 35 and its open upper end rises above the outlet tube 13 in the cooling water chamber 12. A baf-

file 38 extends across the bottom of the tube 38 and volatile gases within the condensing chamber 16 pass around the edges of this baffle and enter the tube 38 through apertures 40. The gases then rise through the tube 38 and escape from the still through holes 41 in the cover 37.

The sheet metal casings, partitions and tube parts, etc., of the still described above are desirably made of sheet copper in view of its high thermal conductivity. Also, the active inner surfaces of the still are preferably coated with pure block tin so as effectually to prevent corrosion and contamination of the distilled water produced.

With the arrangement described above it is but the work of a moment to take the still apart so as to expose all of its active surfaces in order that they can be scrubbed clean (see Fig. 3). For this purpose the intermediate section B is lifted off of the lower section A, the upper section C pulled off of the intermediate section B and the cover 37 removed. It will be noted that the lower end of the feed water supply tube 13 extends loosely into the open top of the cup 14 (Fig. 2) so that these parts offer no impediment to the separation of the still sections or units. When the still has been pulled apart in the manner noted the evaporator pan 19 is entirely open for cleaning. If desired it can be removed entirely from the base casing 18 by simply unscrewing the nipple 22 in the cup 14, which is normally threaded into the evaporator pan to hold it in place. In the same way the active lower and upper surfaces of the domes 27 and 28 are exposed at the opposite ends of the intermediate section 25. In the case of the upper section C the entire lower surface of the case 32 and dome 35 is exposed at the lower end of the section while removal of the cover 37 gives access to the interior of the cooling water chamber. Consequently, all of the parts can be thoroughly flushed out, scrubbed and inspected so as to insure complete purity of the distilled water made in the still.

In the operation of the still described above, a suitable source of raw water is connected to the inlet 18 and the heater 20 turned on by the switch 21. The raw water entering at the inlet 18 fills the cooling water chamber 12 and finally overflows through the pipe 13 through which it passes into the cup 14. This water entering the cup 14 fills the cup and the communicating evaporating pan 19 to the top of the overflow tube 23. Thereafter any excess water is drained off through the overflow tube 23. The water 24 in the evaporating pan 19 is boiled and the water vapor produced passes upward around the edges of the baffle 31 into the tube 38 and thence into the condensing chamber 16. There the water vapor impinges against the water cooling dome 35 and is thus condensed so that it drains down to form a pool 17 in the distillate collecting vessel formed by the partition 28 and casing 25. Upon reaching the level of the outlet 11 the distilled water flows off through this outlet into a suitable receptacle (not shown).

Since the condenser cooling water jacket defined by the casing 32 extends down into the pool of distillate 17, the latter is cooled by an amount depending upon the temperature of the cooling water, which in turn depends to some extent upon the rate of supply of the cooling water. Consequently, the temperature of the outgoing distilled water can be regulated by varying the quantity of cooling water supplied. The still permits of a large degree of flexibility in this re-

spect since even if the amount of cooling water exceeds substantially the still's feed water requirements the excess will be drained off through the pipe 23 as heretofore explained. The operation described continues entirely automatically and without the necessity of supervision. Furthermore, it will be noted that there are no float valves or other moving parts required. As a consequence the still is not subject to wear, nor does it require frequent readjustment.

The ornamental design of the still illustrated herein forms no part of the present invention, but is described and claimed in my copending application for a design patent Serial No. 86,001, filed July 13, 1939, and subsequently issued on November 21, 1939, as Design Patent No. 117,756.

I claim as my invention:

1. The combination of a generally cup shaped distillate collecting vessel having an outlet in its side wall located substantially above the bottom thereof to trap distillate in the vessel to a normal liquid level in the latter equal to the height of said outlet from the vessel bottom, a generally cup shaped sheet metal condenser of substantially lesser diameter than the interior of said vessel nested in the latter and having a deeply concaved bottom forming a dome overlying the central portion of the bottom of said vessel, an annular lower edge portion of said condenser projecting down into the vessel below said normal liquid level so as to be immersed in the distillate trapped in the vessel below said outlet, means for supplying cooling water to said condenser, means above said normal liquid level for conveying vapor between a first chamber defined between the dome and vessel bottom and a second chamber defined between the side walls of the condenser and vessel for condensation of such vapor on both the water cooled outer side wall and inner dome of the condenser, and means for admitting condensable vapor to the central portion of said first chamber.

2. The combination of a generally cup shaped distillate collecting vessel having an annular side wall and a bottom wall humped in its central portion and sloped outward and downward toward its juncture with the side wall, an upstanding conduit projecting through the center of said bottom wall for conveying vaporizing liquid therethrough, a condenser unit removably seated in the top of said cup shaped vessel and including a central upwardly concaved dome disposed to overlie the mouth of said conduit and also including an annular jacket encircling said dome and joined to it at its lower edge to define an annular cooling water chamber about the dome, means for supplying cooling water to said chamber to cool both the dome and jacket, said vessel having an outlet located above the lower edge of the dome and jacket assembly of the condenser unit so that the latter is immersed in the liquid distillate trapped in the vessel below said outlet to cool such distillate, said jacket being disposed in spaced relation to the vessel side wall to define a

chamber therebetween, and means defining a cross-over passage through the condenser unit for conveying vapor from the interior of the dome to the chamber between the jacket and vessel side walls for condensation of the same on the water cooled jacket.

3. In a device of the type described, the combination of an upright cylindrical sheet metal casing section having a distillate collecting pan therein, said pan being apertured for the upward passage therethrough of vapor, a condenser unit comprising an annular sheet metal member dimensioned to be received in the upper portion of said casing section in spaced relation to the side wall of the latter and also including a dome wall closing the top of the open center of said annular member, said annular member defining interiorly thereof a cooling water chamber with an opening in the top thereof into the interior of said annular member, an annular flange encircling said annular member and fixed thereto, said flange extending laterally of said member and removably seated on the upper edge of said casing to support said member therefrom, and a removable lid for closing said opening in the top of said annular member.

4. A still comprising, in combination, three generally tubular casing sections removably supported one on another in superimposed and axially aligned relation, the upper casing section being of lesser cross sectional area than the intermediate section and nested down into the interior of the latter, the lower section having an evaporating pan therein, the intermediate section having vertically spaced upper and lower transverse partitions therein constituting respectively a distillate collecting pan and a top wall of an evaporating chamber above said evaporating pan with a heat insulating dead air space between said partitions, means for supplying raw water to said evaporating pan, an upstanding conduit extending centrally through said partitions to convey vapor from a point above the evaporating pan to a point above said distillate collecting pan, an upwardly concaved dome overlying the mouth of said conduit and joined at its lower edge to the lower edge of said upper casing section to define an annular cooling water chamber about said dome, means for supplying cooling water to said annular chamber, said intermediate casing section having a distillate outlet therein located above the lower edge of said annular water chamber so that the latter is immersed in liquid distillate trapped in the distillate collecting pan below said outlet to cool such trapped distillate, the exterior of said upper casing section being spaced from the interior of the intermediate casing section, and means defining a cross-over passage through said dome and upper casing assembly for conveying vapor from the interior of the dome to the space between the walls of said upper and intermediate casing sections at a level above said distillate outlet.

ALEXANDER I. NEWMAN.
